DESIGN FOR A TEXTILE FABRIC

William Heller, New York, N. Y., assignor to Fairy Silk Mills, Shillington, Pa., a corporation

Application January 12, 1934, Serial No. 50,381

Term of patent 3½ years

To all whom it may concern:

Be it known that I, WILLIAM HELLER, a citizen of the United States, residing at 275 Central Park West, in the county of New York and State of New York, have invented a new, original, and ornamental Design for a Textile Fabric, of which the following is a specification, reference being had to the accompanying drawing, forming a part thereof.

The figure is a plan view of a portion of the fabric, showing my new design.

The dark area on the drawing represents a background. The open mesh appears against the dark background.

I claim:

The ornamental design for a textile fabric, as shown and described.

WILLIAM HELLER.
